United States Patent Office

Des. 215,219

Patented Sept. 16, 1969

215,219

LECTERN

Jacob De Vries, 908 W. 18th Ave., Vancouver,
British Columbia, Canada

Filed Aug. 12, 1968, Ser. No. 13,113

Term of patent 14 years

Int. Cl. D6—01

U.S. Cl. D33—10

FIGURE 1 is a side elevation of the lectern showing my new design, and

FIGURE 2 is an isometric view thereof.

The dominant features of my new design are shown in solid lines in the drawing.

I claim:

The ornamental design for a lectern, substantially as shown and described.
